UNITED STATES PATENT OFFICE.

D. FRANKLIN BLIGHTON, OF BUFFALO, NEW YORK.

TRACK-BOLT LOCK.

SPECIFICATION forming part of Letters Patent No. 278,678, dated June 5, 1883.

Application filed April 20, 1883. (No model.)

To all whom it may concern:

Be it known that I, D. FRANKLIN BLIGHTON, a citizen of the United States, residing in Buffalo, in the county of Erie and State of New York, have invented certain new and useful Improvements in Track-Bolt Locks, of which the following is a specification.

The object of my invention is to provide a simple and durable means for locking a track-bolt, which will be fully and clearly hereinafter shown by reference to the accompanying drawings, in which—

Figure 1 is an end view of a rail and fish-joint, showing the device complete and together. Fig. 2 is an inside view of the lock. Fig. 3 is a horizontal section through line X X, Fig. 1. Fig. 4 is a top view of the locking or tightening thimble, and Fig. 5 is a side elevation of a portion of a fish-joint.

20 *a* is the rail; *a'* *a''*, the fish-joint. The plate *a'* is provided with an oblong hole, *a''*, or of any other suitable form for preventing the nut *a⁴* from turning therein. *a⁵* represents the bolt. *a⁶* is the tapering thimble, adapted to fit in the 25 fish-plate *a'*, and of an oblong form, or such form as will not turn in the plate. It has an opening, *a⁷*, down through the side, and in

some cases a small opening, *a⁸*, part way down in the other side. The nut *a⁴* is provided with a flange, *c*, the portion *a⁴* being adapted to fit 30 the hole in the fish-plate.

It will now be seen that by putting the nut *a⁴* in place and inserting the bolt through the thimble, fish-bolts, and rail, and then screwing up the bolt, the thimble will tighten around 35 it in proportion as it is screwed up, and thereby lock it or hold it securely and prevent it from turning. The nut *a⁴*, when in position, is drawn in against the flange or shoulder *c*, thereby locking it so it is impossible to turn it, and the 40 bolt is locked by the thimble *a⁶*, as before mentioned.

I claim as my invention—

25 A track-bolt lock consisting of the bolt *a⁵*, a nut, *a⁴*, adapted to fit the opening in the fish-plate without turning in it, and a tapering 45 thimble having an opening on one side, also adapted to fit the fish-plate without turning, in combination with a bolt, *a⁵*, for the purposes described.

D. FRANKLIN BLIGHTON.
